UNITED STATES PATENT OFFICE.

WILHELM PAPE, OF CHARLOTTENBURG, GERMANY, ASSIGNOR TO GENERAL ELECTRIC COMPANY, A CORPORATION OF NEW YORK.

REGULATOR FOR TAPPED TURBINES.

1,064,763.

Specification of Letters Patent. Patented June 17, 1913.

Application filed January 21, 1913. Serial No. 743,336.

To all whom it may concern:

Be it known that I, WILHELM PAPE, a subject of the King of Prussia, residing at Charlottenburg, Germany, have invented 5 certain new and useful Improvements in Regulators for Tapped Turbines, of which the following is a specification.

This invention relates to elastic-fluid turbines, and especially to those in which 10 vision is made for extracting a portion of the steam for industrial purposes, after it has passed through the higher stages of the machine. In such turbines, the high pressure inlet valve is usually controlled by a 15 speed governor, while the overflow valve, which admits the surplus steam from the extraction chamber to the low pressure stages of the machine, is controlled by a pressure-responsive device, exposed to the 20 pressure in said chamber. In the practical operation of such a system, certain defects become apparent. If the load varies, the 25 number of revolutions per minute will vary inversely with the load. An increase of load will cause a wider opening of the admission 30 valve by the speed governor, and the pressure in the extraction chamber, or tapped stage, rises in accordance with the greater quantity of steam delivered thereto. The 35 rise of pressure causes the pressure-responsive device to open the overflow valve. This brings into play the low pressure bucket wheels to carry the increased load, so that the speed comes up again, and the speed 40 governor reduces the opening of the admission valve. This again causes another functioning of the pressure device controlling the overflow valve, tending to close said valve more or less. Thus it appears that the two 45 regulating devices can swing into a state of rest only gradually, producing a species of "hunting" as the speed rises and falls. The effect is quite similar in case the steam consumption varies in the industrial system supplied by the extraction pipe. If more steam 50 is consumed, then the pressure-responsive device closes the overflow valve by a corresponding amount. This tends to lessen the work done by the turbine, so that the speed 55 governor must open the high pressure admission valve enough to reestablish the former amount of work-performance and enable the turbine to carry its load. Each of the two regulating devices thus influences the other, but not instantly, so that between

the operations of the two quite a long oscillation easily occurs, before a condition of equilibrium is finally attained.

The present invention is designed to obviate this difficulty. The speed governor is arranged to act upon both valves in such a manner that the pressure in the extraction chamber remains constant. If therefore the load varies, the speed governor regulates the steam supply without in any way affecting the pressure in the tapped stage. The pressure-responsive device is so arranged that it opens or closes the overflow valve or the high pressure admission valve according to the steam consumption, while at the same time it influences the speed governor rods in such a manner that the load on the machine and thus also the number of revolutions per minute of the turbine will remain constant.

In the accompanying drawings, Figure 1 75 is a diagram of mechanism embodying my invention, the movements of the two regulators being communicated directly to the two valves; Fig. 2 represents a system in which indirect oil transmission is employed; and 80 Fig. 3 shows a tapped turbine controlled by valve mechanism of the previous figures.

Referring first to Fig. 1, the high pressure admission valve 1 is connected to a lever 2 fulcrumed at 3 and articulated by a pivoted block 4 to one end of a lever 5, fulcrumed at 6 and connected by a link 7 to a floating lever 8, to which is connected the stem of the overflow valve 9. The lever 8 is also pivoted to the rod 10 of a piston 11 90 working in a cylinder 12, and biased in one direction by a spring 13 which acts in opposition to the fluid pressure of the steam in the extraction chamber of the turbine, conveyed to said cylinder by the pipe 14. This device forms the pressure regulator for controlling the overflow valve 9. The speed governor 15 has a movable collar 16 which is pivoted to a second floating lever 17, connected at an intermediate point to a link 18 95 which is pivoted to the block 4. The other end of the lever 17 is pivotally connected to a lever 19 which is fulcrumed to a support 20 capable of longitudinal adjustment along said lever. At 21 the lever 19 is pivoted to the rod 10 of the overflow valve. The operation of these parts is as follows: If the load on the machine increases, the speed governor collar 16 drops and pulls down on the link 18, which operates the levers 2 and

5 and opens both the valves 1 and 9; the adjacent ends of the levers 8 and 17 being held stationary by their connections to the rod 10 of the pressure-responsive device. 5 The surplus steam admitted by the valve 1 is therefore passed on to the low pressure stages of the turbine to assist in carrying the increased load, without changing the pressure in the tapped stage, or extraction chamber. 10 As the same effect is produced with a falling load, it appears that suitable regulation by the speed governor will be accomplished without in any way affecting the pressure-responsive device. If, now, the 15 consumption of steam in the industrial system varies, assume, for example, that it increases, with a corresponding drop in the pressure in the extraction chamber. In accordance with this decrease in pressure, the 20 piston 11 is forced down by the spring 13 and actuates the floating lever 8 to close the overflow valve, said lever tending to fulcrum on the stationary link 7. But at the same time, the levers 19, 17, 5 and 2 are changed 25 in their positions, and in such manner that the two valves are opened. The object of this simultaneous opening is to increase the flow of steam through both the high and the low pressure stages of the turbine without 30 affecting the pressure in the extraction chamber, in order to make up for the decrease in the work performed in the low pressure part of the turbine by the closing of the overflow valve, and thus to maintain 35 constant the total amount of work performed by the turbine notwithstanding the greater consumption of steam in the industrial system. It thus appears that with varying steam consumption in the industrial 40 system, the pressure-responsive device maintains constant the sum of the production of energy in the high and low pressure portions of the turbine, irrespective of the speed governor, and at the same time keeps 45 a constant pressure in the tapped stage. Under the most unfavorable conditions, the speed governor has only to equalize small inaccuracies of operation. By shifting the adjustable fulcrum 20 the ratio of the leverages acted upon by the pressure-responsive device may be varied, so that the influence upon the work performed, exerted by the shifting of the valve stems may be exactly adapted to the variation in work caused by 50 the movement of the overflow valve.

In Fig. 2, the movements of the two valves

are effected by means of hydraulic motors 22, controlled by pilot valves 23 which are acted on by the two regulating devices in a manner which will be readily understood by a comparison with Fig. 1.

In accordance with the provisions of the patent statutes, I have described the principle of operation of my invention, together with the apparatus which I now consider 60 to represent the best embodiment thereof; but I desire to have it understood that the apparatus shown is only illustrative, and that the invention can be carried out by other means.

70 What I claim as new and desire to secure by Letters Patent of the United States is,—

1. In a tapped turbine, the combination with a high pressure admission valve, and an overflow valve between the tapped stage 75 and the low pressure portion of the turbine, of a speed governor arranged to open and close said valves simultaneously, and a pressure-responsive device having the same control of said valves, and means whereby the 80 pressure-responsive device can also move the overflow valve in the opposite direction, so that with variable extraction of steam the load on the turbine may remain constant, and with a varying load the steam supplied 85 from the tapped stage remains practically constant.

2. In a tapped turbine, the combination with a high pressure admission valve and an overflow valve between the tapped stage 90 and the low pressure portion of the turbine, of two articulated levers, one of which is connected to the high pressure admission valve, a floating lever connected to the overflow valve and linked to the other of the articulated levers, a pressure-responsive device connected to said floating lever, an adjustable lever pivoted to the rod of the pressure-responsive device, a speed governor, a second floating lever actuated by the speed 95 governor and pivoted to said adjustable lever, and connections between said second floating lever and the joint between the articulated levers.

In witness whereof, I have hereunto set 105 my hand this thirty-first day of December, 1912.

WILHELM PAPE.
